The ornamental design for a container tin with cutter, as shown and described.

DESCRIPTION

FIG. 1 is an isometric view of a container tin with cutter, showing my new design in a fully opened state;

FIG. 2 is an isometric view thereof, in a partially opened state;

FIG. 3 is a plan view thereof;

FIG. 4 is a right side elevation view of the container tin with cutter of FIG. 1 in a fully closed state, the left side being a mirror image thereof;

FIG. 5 is a front elevation view thereof;

FIG. 6 is a rear elevation view thereof;

FIG. 7 is a top, rear, and left side isometric view thereof;

FIG. 8 is a top, front, and right side isometric view thereof;

FIG. 9 is a top plan view thereof; and,

FIG. 10 is a bottom plan view thereof.

The drawings show a right side elevational view of the container tin with cutter but do not show a left side elevational view as this is a mirror image of the right side elevational view.
